UNITED STATES PATENT OFFICE.

ALBERT J. LOEPSINGER, OF EDGEWOOD, RHODE ISLAND.

AUTOMATIC SPRINKLER.

Application filed December 26, 1919. Serial No. 347,468.

To all whom it may concern:

Be it known that I, ALBERT J. LOEPSINGER, a citizen of the United States, residing at Edgewood, in the county of Providence and 60 State of Rhode Island, have invented certain new and useful Improvements in Automatic Sprinklers, of which the following is a specification.

This invention relates to improvements in 10 automatic sprinklers. More particularly it relates to fire extinguishing apparatus in which a chemical reaction occurs, producing a gas which is ordinarily carbon dioxide, by union of two liquids. The liquids may be 15 respectively acid and alkali, and if desired one may carry some material such as Peruvian soap bark which causes the free formation of bubbles with relatively tough film, according to practices already well known. 20 In the use of such a system with automatic sprinklers it is desirable that the liquids should meet at the sprinkler. Sprinklers have been devised in which the sprinkler valve has two valve faces and two seats, one 25 controlling each liquid, but there are difficulties and objections involved in such. It is a purpose of the present invention to provide means by which a single simple sprinkler of the ordinary type with one valve seat, as used for water, can operate to discharge the mixed liquids with such foam as is formed as a result of their mixture at the 30 sprinkler. The invention is illustrated as it may be applied to a dry pipe system in 35 which the two systems of distributing pipes respectively are each normally filled with air at a pressure below that at which the liquids themselves are held in their respective supply chambers and pipes. When a 40 sprinkler is opened by heat, the air escapes and the dry pipe valves automatically admit the liquids into their distributing pipes. The liquids in these pipes come together at 45 every sprinkler, ready to discharge in case it should open. The resulting chemical reaction will be premature if the sprinkler does not open. And if one liquid should arrive at the sprinkler before the other, and flow by it into the pipe of the other liquid 50 the meeting would occur at some indeterminate place where there is no sprinkler. In that case there might be undesirable generation of gas and pressure at various spots through the system, and might be at some 55 sprinklers one liquid or the other, but not both. It is therefore among the objects of

the present invention both to provide for mixing at each sprinkler, for discharge when the sprinkler is open, and to prevent mixing thereat when it is closed, and to prevent the liquids from meeting except at the 65 sprinklers. These ends are attained by providing at each sprinkler station a chamber having an inlet from each of the two liquid systems, and whose outlet is closed by the 70 sprinkler, each entrance having a check valve which normally tends to close itself independently of the effect of fluid flow. It is another object to accomplish the result by a simple and inexpensive device, in a 75 structural and manufacturing sense.

In the embodiment illustrated there is a cross connection between the pipes carrying the separate liquids; and a section of this is set off by opposed check valves arranged 80 to be seated by gravity. The space between them constitutes a mixing chamber and is tapped to receive a single orifice sprinkler of any suitable or ordinary type. When the 85 sprinkler opens, in service, the two liquids come together in the chamber and the reaction between them aids in forcing them and the products of their reaction out through the sprinkler. If a particular 90 sprinkler does not open, but some other 95 sprinkler opens, so that air of the system escapes, the two liquids will likewise meet at each cross connection between their respective systems of distributing pipes. If 100 they reach an unopened head simultaneously, the slight reaction which occurs generates gas which makes pressure in the chamber and so closes both check valves, thus preventing further inflow of either liquid so long as the sprinkler remains closed; and preventing further reaction, beyond 105 what may occur within the chamber. If one liquid reaches the sprinkler before the other, it may fill so much of the chamber as remains unfilled by pocketed air, but is prevented from passing into the other pipe by the check valve thereof. The second liquid arriving later at that check valve is prevented from opening it, so as to pass in any considerable body, by the approximate balance between its pressure and that of the liquid which first arrived, and by the action of gravity which in this condition of equilibrium of pressures exerts a "balance of power" 110 that holds the check valve closed. However if a little passes into the chamber on the first rush, the reaction which then occurs

2
curs generates gas which increases the pressure in the chamber over the hydrostatic pressure, and holds both check valves tightly closed. In result therefore the invention 5 provides a mixing chamber within the system so that the fluids meet and issue from a single orifice, when the sprinkler is open; and meet without objectionable mixing if the sprinkler is closed; or if a small amount 10 of mixing occurs in the latter case, that takes place in the closed chamber and the mixing which does thus occur is effective to prevent further mixing.

The apparatus and ingredients mentioned 15 for embodying the invention are merely illustrative, as variations may be made in many respects. It is intended that the patent shall cover by suitable expression in the appended claims whatever features of patentable novelty exist in the invention disclosed.

In the accompanying drawing, the figure represents in side elevation a medial section through a sprinkler and adjacent parts in 20 apparatus embodying the invention.

Referring to the drawing, 10 indicates an automatic sprinkler which may be of any ordinary or suitable type as used for water, closing an orifice 11 in fire extinguishing apparatus installed in a building, comprising two "dry pipe" distribution systems, one indicated in the drawings by the pipe 12, and the other by the pipe 13; one carrying a liquid such as an acid, and 25 the other a liquid such as an alkali, which when mixed generate carbonic acid gas. These may be arranged to produce foam according to well known methods; or other liquids may be used in place of them. The 30 sprinkler is set in a chamber 14 to which liquid in the pipe 12 has access through a check valve 15, and to which liquid in pipe 13 has access through a check valve 16, each valve being arranged to be closed normally by gravity and having a substantial 35 weight to make the force of gravity controlling even in the presence of some degree of hydrostatic pressure opposing it. As illustrated these valves are pivoted respectively at 15' and 16' although a spring or other equivalent method of closure might be substituted, and the seats 25 and 26 respectively for these valves are set at an angle of about 45°. Openings 20 closed by 40 plugs are provided for access to the valves; and an outlet 21 for drainage, normally 45 closed, may also be provided.

In operation the pipes 12 and 13 each normally contain only air, as does the chamber 14. Upon the automatic opening of the 50 sprinkler 10 under abnormal heat, each pipe loses its contained air, and by the action of well known apparatus not shown, such as a dry pipe valve, each pipe receives a supply of its particular liquid. As discharge 55

occurs through the outlet 11 these liquids will meet in the chamber 14. Chemical reaction follows and their expulsion with increased force by the gases thus generated. If however the sprinkler seen in the drawing remains closed, and it is the opening of some other sprinkler which has occasioned the escape of air and substitution of liquids in the pipes 12 and 13, that liquid which arrives first at the particular sprinkler seen in the drawing will readily pass its own check valve, which may be assumed to be valve 15, and owing to its higher pressure will enter the chamber 14 to some extent at least, but will be stopped by the 60 check valve 16 from passing on into the pipe 13. The other liquid, arriving later at valve 16 through pipe 13, will have hydrostatic pressure no greater than that of the first liquid, because the system, by devices 65 not shown, ordinarily makes the pressure equal. The weight of the valve therefore will be sufficient to maintain it closed, keeping the liquids apart and preventing chemical reaction. If however, the liquid arriving through pipe 13 should come with sufficient impetus to open the valve 16 against the air-cushion within, the reaction which follows would be within the chamber; and the gas pressure generated thereby 70 would result in forcing both check valves more firmly on their seats, so that no reaction would occur beyond that due to the liquid within the chamber.

Meanwhile both liquids are at the sprinkler ready to mix and discharge if and when that sprinkler head shall open, and are controlled and discharged by a single sprinkler of ordinary type.

The embodiment of the invention thus 75 described illustrates how it may be applied with any plural number of liquids, in case it is desired to control the mixing of more than two.

I claim as my invention:

1. In fire extinguishing apparatus the combination of pipes for supplying two liquids, a mixing chamber, and an automatic heat-controlled valve discharging therefrom; the chamber being normally 80 filled with air and connected for access for contents of both of said pipes to it when said automatic valve is closed and provided with automatic means preventing the passage of contents of either pipe through said chamber into the other pipe.

2. The combination, with dry pipes for supplying two liquids, of a mixing chamber fed by both pipes, an automatic heat-controlled single-seated valve closure for discharge, and means whereby the liquid which first arrives at the mixing chamber automatically holds the same closed against entrance of the other liquid so long as said discharge valve remains closed.

3. The combination, with pipes for supplying two liquids, of a mixing chamber fed by both pipes, check valves at the entrance of each pipe into the chamber preventing passage of chamber contents into either pipe, and an automatic heat-controlled valve for discharge from the chamber.
4. The combination, with pipes for supplying two liquids, of a mixing chamber fed by both pipes, self closing check valves at the entrance of each pipe into the chamber preventing passage of chamber contents into either pipe, and an automatic heat-controlled valve for discharge from the chamber.
5. The combination with pipes for supplying two liquids, of a mixing chamber fed by both pipes, an automatic heat-controlled valve for discharge from the chamber, and self closing check valves located close to the discharge valve, whereby the mutual contact of the liquids is restricted to the space in immediate proximity to the discharge valve.
6. In a sprinkler system, a method of preventing premature mixing of chemically re-

acting liquids present at a closed sprinkler, comprising the admission of small portions of each liquid to a closed chamber having self closing inlet check valves, thereby producing a preliminary minor reaction generating pressure; and by said pressure maintaining the inlets closed.

7. A sprinkler for automatic fire extinguishing apparatus, comprising a discharge valve having heat controlled closure in combination with a small casing forming a union between supply pipes for liquids and the discharge passage; said casing constituting a chamber for mixture and reaction of the liquid fluids, and having a check valve between the chamber and each of the supply pipes; the said chamber and supply pipes being ordinarily filled with air, and the said check valves preventing liquid when released from rushing from either pipe into the other.

Signed at Boston, Massachusetts, this 20th day of December, 1919.

ALBERT J. LOEPSINGER.
